UNITED STATES PATENT OFFICE

JOSHUA WAGNER, OF BROOKLYN, NEW YORK, ASSIGNOR, BY MESNE ASSIGNMENTS, TO
DIAGONAL CORRUGATED PATENT CORPORATION, OF NEW YORK, N. Y., A CORPORA-
TION OF NEW YORK

CORRUGATING MACHINE

Application filed June 18, 1929. Serial No. 371,909.

The invention relates to a machine for producing corrugations in sheet material which run obliquely across the sheet, such a machine, although useful for other purposes, being particularly advantageous in the manufacture of corrugated paper boxes of the type described in Patent No. 1,620,174 entitled "Carton" and issued to me on March 8, 1927, wherein the corrugations run obliquely across the sides of the box. Blanks for boxes of the above type can be more economically made from corrugated paper board having the oblique corrugations above referred to, than from corrugated paper board having the transverse corrugations which are produced by machines of the types now in use.

The formation of oblique corrugations, however, presents certain difficulties, particularly in maintaining a continuous feeding of the web in the direction of its length, and at the same time avoiding tearing of the sheet during the operation of forming the oblique corrugations. The present invention aims to avoid the above and other difficulties in such manner as to enable the machine to form oblique corrugations without injury to the sheet and at practical speeds. Further objects and advantages of the invention will be in part obvious and in part specifically pointed out in the description hereinafter contained which, taken in conjunction with the accompanying drawings, discloses a preferred embodiment of the invention; such embodiment, however, is to be considered merely as illustrative of its principles. In the drawings—

Fig. 1 is a plan view with certain parts cut away of a corrugating machine constructed in accordance with the invention.

Fig. 2 is a side view with certain parts cut away of the machine shown in Fig. 1.

The invention is illustrated as applied to a corrugating machine wherein the paper web 1 to be obliquely corrugated is fed continuously in a lengthwise direction, between a pair of mating corrugated dies which are provided with corrugations running obliquely to the path of travel of the sheet, which dies successively engage along oblique lines

extending all the way across the sheet, and thereby form the entire length of each corrugation simultaneously, and form the complete corrugations successively. With this mode of operation the contraction of the paper web or sheet, which necessarily occurs when the corrugations are formed, takes place in a lengthwise direction, avoiding any transverse contraction sufficient to place undue strains on the sheet as it passes between the dies.

In the illustrated form of the invention, one set of corrugated dies is carried by an endless conveyor made up of chain-links 2 which pass around sprocket wheels 3, which latter are supported on suitable frames 4. As shown the oblique corrugations are formed in flat die members 5 mounted on alternate chain-links 2, and the upper flight of the conveyor runs over a pair of guide rails 6, which serve to hold the corresponding dies in plane and abutting relation. As shown the chain-links 2 are provided with rollers 7 which run along the guide rails 6.

The remaining die member is shown in the form of a roller 8 mounted obliquely above the traveling conveyor, and having longitudinal corrugations adapted to mesh successively with the corrugations of die members 5, when the conveyor travels forwardly and the roller 8 rotates about its oblique axis parallel to the corrugations of the conveyor. Preferably the roller 8 is provided with bearings 9 of the thrust type at its opposite ends.

In the operation of the machine the paper web 1 to be obliquely corrugated, will be fed along with the traveling conveyor until the sheet passes under the roller 8, when the oblique corrugations will be successively formed in the sheet, each corrugation being simultaneously formed along its entire length as above referred to, and the contraction of the sheet during the corrugating operation taking place in a lengthwise direction as above referred to.

The roller 8 in the illustrated form of the invention is not positively driven, but derives its motion by meshing with the corrugations of the traveling conveyor, as above

described. A suitable number of stripper fingers 10, operating in grooves 11 in roller 8, may be employed to separate the corrugated sheet from the roller, these stripper fingers being shown as mounted upon a bar 12 extending across the machine in back of roller 8.

If desired, stripping members 13 may also be employed to separate the corrugated sheet from the lower die, operating in conjunction with grooves 14 in such die.

It will be understood that the web 1, after being corrugated, will usually have one or more facings applied thereto, to make single or double faced corrugated paper board, but as means already known to the art may be employed for the above purpose, I do not deem it necessary to describe the same herein.

While a specific embodiment has been described it should be understood that many changes may be made therein without departing from its principles as set forth in the appended claims.

I claim:

1. A machine for obliquely corrugating sheet material, having a corrugated traveling conveyor wherein the corrugations run oblique to its path of travel, a corrugating roller having longitudinal corrugations, said roller being rotatable about an axis parallel to the first mentioned corrugations.

2. A machine for obliquely corrugating sheet material, having a corrugated traveling conveyor wherein the corrugations run oblique to its path of travel, and a corrugating roller having corrugations adapted to mesh with the conveyor corrugations and thereby obliquely corrugate a sheet traveling with said conveyor.

3. A machine for obliquely corrugating sheet material, having means for continuously feeding a sheet in a lengthwise direction, and including corrugating members on opposite sides of the path of travel of the sheet which have complementary corrugations each extending obliquely across the path of travel of the sheet and adapted to engage successively substantially all the way across the sheet, thereby to form diagonal corrugations successively in the sheet and contract the latter in a lengthwise direction as the corrugations are formed.

4. A machine for obliquely corrugating sheet material, having a corrugated traveling conveyor wherein the corrugations run oblique to its path of travel, and a corrugating roller having corrugations adapted to mesh with the conveyor corrugations and thereby obliquely corrugate a sheet traveling with said conveyor, said conveyor being of the endless type and having a plurality of flat dies carrying its first mentioned corrugations and adapted to abut when in operating position.

5. A machine for obliquely corrugating sheet material, having a corrugated traveling conveyor wherein the corrugations run oblique to its path of travel, a corrugating roller having corrugations adapted to mesh with the conveyor corrugations and thereby obliquely corrugate a sheet traveling with said conveyor, said conveyor being of the endless type and having a plurality of flat dies carrying its first mentioned corrugations and adapted to abut when in operating position, and a guide member engaging the operating flight of said conveyor adapted to maintain the corresponding dies in plane and abutting relation. 70

6. A machine for obliquely corrugating sheet material having a pair of corrugated dies, one of said dies being in the form of a roller rotating on an axis oblique to the path of travel of the sheet to be corrugated, and the corrugations running lengthwise of said roller, and the remaining die being also corrugated obliquely with respect to the path of travel of the sheet and being adapted to engage tangentially with successive corrugations of the roller as the latter rotates. 80

7. A machine for obliquely corrugating sheet material having a pair of corrugated dies, one of said dies being in the form of a roller rotating on an axis oblique to the path of travel of the sheet to be corrugated, and the corrugations running lengthwise of said roller, and the remaining die being also corrugated obliquely with respect to the path of travel of the sheet and being adapted to engage tangentially with successive corrugations of the roller as the latter rotates, said remaining die moving in the direction of travel of the sheet. 95

In testimony whereof I have signed my name to this specification.

JOSHUA WAGNER.
